(57) **CLAIM**

The ornamental design for a handle for a razor as shown and
described.

DESCRIPTION

FIG. 1 is an isometric front view of a handle for a razor.

FIG. 2 is a front view of the handle for a razor.

FIG. 3 is a top view of the handle for a razor.

FIG. 4 is a right side view of the handle for a razor.

FIG. 5 is a rear view of the handle for a razor.

FIG. 6 is a bottom view of the handle for a razor; and,

FIG. 7 is a left side view of the handle for a razor.

The evenly-spaced broken lines illustrate portions of the
handle for a razor and form no part of the claimed design.
The dot-dash broken lines illustrate a boundary to the
claimed design and form no part thereof.
